UNITED STATES PATENT OFFICE.

ALBERT P. CANNON, OF FARMINGDALE, MAINE.

FASTENING FOR REFLECTORS UPON TUBULAR LANTERNS.

SPECIFICATION forming part of Letters Patent No. 274,170, dated March 20, 1883.

Application filed February 10, 1883. (Model.)

To all whom it may concern:

Be it known that I, ALBERT P. CANNON, of Farmingdale, in the county of Kennebec and State of Maine, have invented certain new and useful Improvements in Fastenings for Reflectors upon Tubular Lanterns; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a tubular lantern provided with my improved reflector, and Fig. 2 is a similar view of the fastening for the same.

Similar letters of reference indicate corresponding parts in both the figures.

My invention has relation to fastenings for reflectors upon tubular lanterns; and it consists in the improved construction and combination of parts of the same, as hereinafter more fully described and claimed.

The fastening consists of three pieces of stout wire, which are bent and connected in such a manner as to clamp the reflector A, which is circular, and may be of any desired construction as regards concavity or form of reflecting-surface, and to clamp the lower horizontal parts, B, and upper vertical parts, C, of the tubes of a tubular lantern. The ends D of the upper wire, E, are bent forward and terminate in inwardly-bent hooks F, which clamp the upper parts, C, of the tubes, while the inner portion, G, is coiled at its center to form a spring-coil, H, which gives additional springiness to the clamping portions D F, and serves as an eye for suspending the lantern from a nail or hook. The lower ends, I, of the second wire, J, extend forward, and are bent back and again curved forward at K to form clamps for the horizontal lower portions of the tubes, while their inner portions, L, are doubly bent to receive and hold the lower edges of the reflector. From these bends the wires pass upward, resting against the back of the

reflector till they reach the upper edge of the same, where they are bent forward and downward, first forming eyes M, in which the straight portions of wire E rest, and thereupon clamping over the upper edge of the reflector. These clamping portions N of the wire are again doubled upward, over the edge of the reflector, and downward, slightly rearward, where they are coiled at O, from which the central portion of the wire forms a downward-projecting clamp, P, adapted to be clamped over a bail, flat rail, or other thin horizontal object. The straight parallel portions Q of the wire, which pass up back of the reflector, are slightly bent or dented at their lower portions, adapted to hold the third piece of wire, R, which passes across the back of the reflector and holds the ends of wire J together, the latter passing through eyes S—one in each end of the wire—which clasp around the dented places in the parts Q.

It will be seen that if one reflector becomes tarnished or otherwise useless a new one may be inserted in a moment of time without the use of any tools, and that the lantern may be suspended or clamped upon any place by means of the clamp P or coil H, the fastening clamping the lantern rigidly when applied.

Having thus described my invention, I claim and desire to secure by Letters Patent of the United States—

The fastening for reflectors upon tubular lanterns, consisting of the piece E, bent to form hooks F and coils H, the piece J, bent to form clamps K at its lower ends, reflector-clamps L and N and downward-bent clamp P, and the cross-piece R, holding the ends of wire J together, the whole constructed and combined to operate as and for the purpose shown and set forth.

In testimony that I claim the foregoing as my own I have hereunto affixed my signature in presence of two witnesses.

ALBERT PORTER CANNON.

Witnesses:

MARTIN L. CANNON,
A. C. STILPHEN.
